UNITED STATES PATENT OFFICE.

JOHN EDWARD OGDEN, OF BROOKLYN, NEW YORK.

TORSIONAL-GRIP CABLE-HANGER.

1,151,215.

Specification of Letters Patent. Patented Aug. 24, 1915.

Application filed January 20, 1914. Serial No. 813,171.

To all whom it may concern:

Be it known that I, JOHN EDWARD OGDEN, a citizen of the United States of America, and a resident of Brooklyn, Kings county, and State of New York, have invented certain new and useful Improvements in Torsional-Grip Cable-Hangers, of which the following is a specification, reference being had to the accompanying drawings, forming a part thereof.

My invention relates to cable hangers and the like, and has special reference to such hangers as are adapted for supporting a telephone cable from a messenger wire.

One object of my invention is to provide a simple and effective device of this character that shall have a torsional grip on the messenger wire and be susceptible of ready application thereto.

Another object is to provide a structure which may be manufactured in large quantities at a relatively small expense.

Other objects and advantages will be set forth hereinafter, and in order that my invention may be thoroughly understood, I will describe the same in the following specification, and then point out the novel features thereof in appended claims.

Referring to the drawings: Figure 1 is an elevation looking at the end of the messenger wire which is shown in section, of a hanger formed in accordance with my invention. An elevation at right angles to that of Fig. 1, showing short lengths of the messenger wire and the cable, is shown in Fig. 2. Fig. 3 is a plan view illustrating the method of applying the hanger to a messenger wire. Fig. 4 is a view corresponding to Fig. 2, showing a modified form of cable hanger which also embodies my invention. A perspective view of the hanger of Fig. 4 is shown in Fig. 5.

The hanger of Figs. 1 to 3 inclusive is preferably made of spring steel wire and is formed to comprise a loop or ring portion A, a torsional grip portion B at one end, in the form of a helix having its axis Y-Y at an acute angle to the plane Z-Z of the loop or ring (see Fig. 3) and a hook portion C at the opposite end. The hook is bent to engage the top, bottom and one side of the messenger wire.

The helical end which constitutes the torsional grip portion B is in the form of a helix of a few number of turns, the distance between adjacent turns being as great as the

diameter of the messenger wire so that it may readily be hooked onto the messenger wire as shown in the drawings. The loop A is slightly open as formed and consequently the end terminating in the hook C is snapped onto the messenger wire by springing it in the direction of the arrow X into the position shown in broken lines in Fig. 3. A tension is thus put upon the helix which acts like a spring and tends to produce a slight kink in the messenger cable because the axis of the torsional grip portion B is, as above stated, at an acute angle to the plane of the loop. The plane of the loop and the axis of the helix are clearly indicated by broken lines in Fig. 3. This torsional grip is one of the principal features of my invention and is, so far as I am aware, entirely original with me. Among the advantages of this grip the following may be mentioned: 1st, by tending to slightly distort the messenger wire the hanger is very firmly located in the position in which it is mounted; 2nd, it is extremely unlikely to become loosened or disengaged by reason of the weight of the cable or for other causes; 3rd, the helix may fit the messenger wire somewhat loosely when its axis is substantially in alinement with the axis of the wire, and consequently it may be applied quickly and yet possess the previously enumerated advantages.

The hanger of Figs. 4 and 5 is similar to that of the preceding figures in appearance but is made double. It comprises a pair of loops E and F, each of which corresponds quite closely to the loop A, an intermediate torsional grip helix G which corresponds to the helix B and has its axis at an acute angle to the planes of the loops which are substantially parallel, and a pair of hooks H and K at its respective ends. Each of these hooks corresponds to the hook C, and each when applied to the messenger wire has a tendency to produce the torsional gripping effect before described.

As in the hanger of Figs. 1 to 3, each of the loops is made slightly open and the arrangement of parts is such that the hooks grip the wire from opposite sides and both act in the same direction with respect to the central helix, in that they tend to still further twist the axis of the helix relative to the axis of the wire.

The size and proportions of the parts of the hangers may be varied, and the material

and the section of the wire employed may be changed from those shown and described, without departing from the spirit and scope of my invention, and I intend that only 5 such limitations be imposed as are indicated in appended claims.

What I claim is:

1. A hanger composed of a single strip of material or wire formed to comprise a pair 10 of loops or rings, an interposed torsional grip having its axis at an acute angle to the plane of the loops or rings, and hooks at the respective ends of the wire of which the hanger is composed.
15. 2. A hanger composed of a single resili-

ent strip of material or wire formed to comprise a pair of loops or rings spaced at a short distance apart and lying in substantially parallel planes, an interposed torsional grip helix between the loops having 20 its axis at an acute angle to the planes of the loops, and oppositely extending hooks formed at the respective ends of the wire.

In witness whereof, I have hereunto set my hand in the presence of two subscribing 25 witnesses, this 19th day of January, 1914.

JOHN EDWARD OGDEN.
